UNITED STATES PATENT OFFICE.

FRANK KUHN, OF DETROIT, MICHIGAN.

ELECTRICAL FLUID-HEATER.

1,119,840.

Specification of Letters Patent.

Patented Dec. 8, 1914.

Application filed September 6, 1913. Serial No. 788,712.

To all whom it may concern:

Be it known that I, FRANK KUHN, a citizen of the United States of America, residing at Detroit, in the county of Wayne and State of Michigan, have invented certain new and useful Improvements in Electrical Fluid-Heaters, of which the following is a specification, reference being had therein to the accompanying drawings:

10 The invention relates to electrical heaters particularly designed for heating fluids, such as gases or liquids, and being particularly adapted for use in connection with carbureters.

15 In the drawings: Figure 1 is a longitudinal section through one construction of heater; Fig. 2 is a similar view showing a modified construction.

My improved heater comprises essentially 20 a tubular casing or conduit, which is lined with insulating material, preferably a series of insulator bushings placed end to end. Within these bushings is arranged a coil forming the resistor element, the terminals 25 being carried out through the ends of the metal casing. There is also provided inlet and outlet connections for the fluid at opposite ends of the casing and by means of which said fluid is caused to flow through 30 the resistor coil to be heated thereby.

In detail, A is a metal tube, preferably threaded at its opposite ends for engagement with the nipples B of fittings C. These fittings are provided with laterally-extending 35 nipples D forming the inlet or outlet conduits, and their ends are stopped by plugs E, which are centrally provided with insulator bushings F for the passage of the electrical terminals. Preferably the mem-

40 ber C is a T-fitting and is internally threaded through its head portion so as to receive at the opposite ends thereof the tube A and the plug E. Adjacent to this plug is an insulator, preferably a mica washer G, 45 which is secured in position by a ring nut H, and adjacent to the latter is a packing material I clamped by a ring nut J and an interposed mica washer K, the construction being such as to form both an insulated and

liquid tight seal between the plug and the 50 chamber within the tube.

The lining for the tube A is formed by a series of insulator bushings L which are placed end to end and form a continuous tube.

M is the resistor coil placed within the bushings L and having its terminal ends N passing through the insulator packing in the plug E.

With the construction as described, either 60 liquid or gas may be passed through the tube by means of the inlet and outlet nipples D, and during such passage will come in contact with the resistor coil. As this coil is supported at all times by the insulator bushings, all danger of short circuit 65 is avoided.

In the modified construction shown in Fig. 2, the same arrangement of metallic casing with a series of insulator bushings 70 and resistor therein is used, but the casing is then inclosed in an outer casing O. The space between the inner and outer casing may be used either for heat insulation, or for the simultaneous heating of air on the 75 outside of the inner casing and for heating of liquid in the interior thereof.

What I claim as my invention is:

1. The combination with a tubular casing of T-fittings at opposite-ends thereof providing laterally-extending fluid inlet and outlet connections, a series of insulator bushings within said casing, a coiled resistor within said bushings and having terminals extending out through the ends of the T-fittings, and insulator and liquid tight plugs in the ends of said T's surrounding said terminals.

2. The combination with a tubular casing of an insulator bushing therein, a coiled resistor within said insulator bushing, a T-fitting at the end of said casing having its stem forming a lateral fluid connection and its head being internally threaded to receive a plug, a terminal for said resistor passing through said plug, and insulator and packing rings comprising a ring nut, an insulator washer and packing material.

3. The combination with a tubular casing, of an insulator bushing arranged therein, a resistor coil within said bushing extending through said casing, a fitting at the end of 5 said casing having an insulated outlet for said resistor coil and a fluid inlet, a second tubular casing surrounding said first-mentioned casing, and means between said cas-

ings for providing heat-insulation for the first-mentioned casing.

In testimony whereof I affix my signature 10 in presence of two witnesses.

FRANK KUHN.
